UNITED STATES PATENT OFFICE

RICHARD M. DILWORTH, OF LAKewood, OHIO, ASSIGNOR TO THE ELECTRO-MOTIVE COMPANY, OF CLEVELAND, OHIO, A CORPORATION OF OHIO

HYDROCARBON MOTOR

Application filed July 25, 1928. Serial No. 295,155.

This invention relates to hydrocarbon motors and particularly to multi-cylinder engines adapted to operate on a four-stroke internal combustion cycle employing low 5 grade fuel. More particularly the invention pertains to a means for and manner of supplying the fuel mixture to the engine and for controlling the same.

In such engines it is customary to provide 10 a starting or idling carburetor with a manifold arranged to supply mixture therefrom to all or a plurality of the engine cylinders. It is also customary to provide separate carburetion devices one for each cylinder arranged 15 to supply running mixture directly thereto.

My invention contemplates an arrangement such as described and has for an object incorporation therein of means whereby 20 the mixture supplied to the engine will be of proper quality regardless of what proportions thereof are supplied by the idling carburetor and by the running carburetion devices.

25 In such an arrangement since the branches of the idler manifold are open at their ends substantially to atmosphere through the running mixture carburetion devices, there will be, during the idling operation of the engine, 30 reverse flow in the manifold due to suction of air thereinto through the several branches. Another object of my invention is to provide means for preventing such reverse flow in the manifold.

35 Further objects and advantages of my invention will be apparent from the following description taken in connection with the accompanying drawings in which Fig. 1 is an elevation view largely in section showing a 40 construction of the carburetion device in which my invention is incorporated, and Fig. 2 is a diagrammatic view showing three engine cylinders and the fuel mixture supply system therefor, my invention being indicated 45 as incorporated therein.

With reference now to the drawings, the carburetion device shown is provided with an air chest or compartment 1 having a removable side wall 2 but open at its upper 50 end to the atmosphere through a screen 3 car-

ried by the wall, the chest having a seat 4 for an air valve 5 mounted upon a shaft 6 which may extend beyond the chest in either direction and carry similar valves of corresponding devices and having connection with a 55 governor or control handle; it being understood that one such carburetion device is provided for each engine cylinder as indicated in Fig. 2. Secured with the chest is a casting 7 adapted as by flange 8 for connection directly with the engine and having a passage 9 adapted for communication with the inlet valve port of one of the engine cylinders, when such connection is made. The chest also has a downward opening 10 communicating with an elbow 11 through air may pass from the chest to a sleeve member 12 fitted in a casting 13 properly secured as a unit with the casting 7 and other parts shown. The member 12 is turned down upon its forward 60 portion to clear a generally cylindrical valve 14 slidable in the bore 15 of the member 13 in which the member 12 is fitted. 65

The valve 14 is closed at its end by a wall 16 and has an opening 17 leading upwardly 75 and adapted to register with the lower end of a passage 18 leading in the casting 7 into the passage 9. The end of the bore 15 is closed as by a plug 19 but a clearance pocket 20 is allowed sufficient to receive the end wall 16 of the valve in its wide open position, that is, when the opening 17 is aligned with the passage 18. The passage 18 extends downwardly beyond the bore 15 as at 18' and communicates with the transverse passage 39 80 in the manifold 40. This manifold has similar connection with the carburetion devices 1a, 1b, of the several remaining engine cylinders and also has communication with a starting and idling carburetion device 33. 85

The valve 14 carries a laterally extending stud 21 engaged by the forked end 22 of the bell crank lever 23 mounted upon a fixed pin 24. The opposite end of the bell crank lever has connection as by a pair of links 25 with the air valve 5, the arrangement being such that the valves 5 and 14 open and close together. 95

The through opening in the sleeve 12 is tapered down to a restricted throat portion 100

26 into which projects a nozzle 27 having a bore 28 communicating by way of the tube 29 with the float chamber 30 having the usual float, not shown, associated with a needle valve and having a fuel supply connection as at 31, whereby liquid fuel is maintained in the nozzle 27 to the proper predetermined level to be picked up from the nozzle by the air stream through throat 26.

10. The passage 9 also converges to a throat portion 32 into which throat portion the passage 18 opens. By the arrangement described it will be apparent that when the valve 14 is at its extreme right hand position, Fig. 1, the valve 5 will be closed and admission to the engine cylinder will be solely from the manifold 40. Likewise when the valve 14 is at its extreme left hand position, Fig. 1, admission to the engine cylinder will be solely through the chest 1.

15. The drawings show the parts in mid-running position and it will be apparent therefrom that air will be induced during the suction stroke of the piston by way of the opening 10, elbow 11, throat 26 of the sleeve 12, valve 14, passage 18 to the passage 9 at the throat 32 thereof. As the air passes the throat 26 fuel is picked up from the nozzle 27 and the parts are so proportioned that an 20 overly-rich mixture will thus be produced. At the same time, however, air is flowing from the chest 1 past the valve 5 and through the passage 9 to properly thin out this mixture. Also, some mixture is delivered from 25 the manifold 40 through the passage 18' past the end wall 16 of the valve 14 and into the passage 18.

30. From the above description it will be apparent that both the idling mixture and the 40 running mixture are arranged to be delivered through adjacent mouths into the passage leading to the cylinder, and that the valve 14 is arranged to control the relative effective openings of these mouths whereby 45 when the opening in the running mixture mouth is relatively great the opening in the idling mixture mouth will be correspondingly relatively small. Further, by virtue of the shape of the valve 14 both mixtures are delivered in a common direction.

50. The result is that as the valve 14 approaches the right hand position, Fig. 1, the running mixture mouth is so restricted as to materially reduce the velocity through the sleeve 12 but at the same time the effective opening of the idling mixture mouth is increased, and the velocity therethrough correspondingly increased. Therefore, although under such 55 conditions liquid fuel picked up from the nozzle 27 will not be properly broken up by the stream through the sleeve 12, yet when this stream meets that of the idling mixture, the relatively high velocity of the latter will serve to properly break up these particles.

60. Under all conditions of intermediate valve

positions, the particles will be still further broken up by the air stream past the valve 5.

Reference is now had to Fig. 2, wherein the parts have reference numerals generally corresponding to those applied to Fig. 1, and

70 wherein pertinent parts of three engine cylinders 41, 41a, 41b, appear diagrammatically represented; the corresponding valves 14, 14a and 14b, being indicated as interconnected by a rod 16a.

75. It will be apparent that were the valves 14 not arranged as described, under light running conditions with a high vacuum

80 in the passages 9, 9a, 9b, and in the manifold 40, under conditions such as that indicated wherein the inlet valve 42 of the cylinder 41

85 is open, the inlet valves 42a and 42b of the cylinders 41a and 41b being closed, air would find its way through the chest 1b into the corresponding leg of the manifold 40. There-

after, upon opening of the valve 42b the valve 95

42 being at the time closed the air in the manifold would have to be drawn out therefrom and into the cylinder 41b before any

47 mixture could enter this cylinder. According to my invention, however, under idling 90 conditions the valves 14, 14a and 14b cut off from the intake system all communication with the atmosphere so that the manifold 40

52 may function properly.

What I claim is:

1. In combination with a multiple cylinder hydrocarbon motor, a plurality of running carburetors one for each cylinder and each arranged adjacent its cylinder for direct delivery thereto, a separate source of fuel mixture supply and manifold means for delivering therefrom to said cylinders, and valve means associated with said carburetors for controlling the relative supply to said cylinders from their carburetors and from said 100 separate source of supply, whereby reverse flow in said manifold is restricted as said carburetors are increasingly drawn upon.

2. In combination with a multiple cylinder hydrocarbon motor, a plurality of running carburetors one for each cylinder and each 110 arranged adjacent its cylinder for direct delivery thereto, a separate source of fuel mixture supply and manifold means for delivering therefrom to said cylinders, and valve

means associated with said carburetors and with said manifold for closing communication between said cylinders and the atmosphere therethrough, whereby when the motor

is to be served by said separate source of 115 supply atmospheric air may be prevented from being drawn into said manifold by way of said carburetors.

3. In combination with a multiple cylinder hydrocarbon motor, a plurality of running carburetors one for each cylinder and each arranged adjacent its cylinder for direct delivery thereto, a separate source of fuel mixture supply and manifold means for delivering therefrom to the several cylinders 125

130

by way of the carburetor delivery passages thereof and valve means associated with said carburetors and with said manifold for selectively closing communication between said 5 cylinders and the atmosphere therethrough, whereby when the motor is to be served by said separate source of supply atmospheric air may be prevented from being drawn into said manifold by way of said carburetors.

10 In testimony whereof I hereby affix my signature.

RICHARD M. DILWORTH.
